CLIFFORD G. MOON, OF ANTHONY, RHODE ISLAND.

FEELER MECHANISM FOR LOOMS.

Application filed July 3, 1928. Serial No. 290,141.

My invention relates to a feeler mechanism for the filling replenishing type of looms, and is purposed to indicate impending filling exhaustion and to set into operation the filling 5 replenishment mechanism.

An object of my invention is to provide a filling mechanism adapted for use upon cops or bobbins carrying a finer or more delicate yarn or filament than has hitherto been practicable. Heretofore the resistance of the feeler to the beat of the lay has been excessive except upon coarse yarn which is stronger, and which receives less blows or beats than a fine filament which is, because of its relatively 10 slow discharge from the bobbin, subjected for a longer period to the blows. A heavy beat upon an artificial silk filament so marks the latter as to be visible after the dyeing. It is equally essential in a fine yarn manipulation that no serrations upon the feeler contact therewith.

Further objects of my invention are to insure instant and accurate operation of the device regardless of the accurate placing or 15 boxing of the cop; to avoid the waste of material and labor incident to injury of the yarn or filament occasioned by the mechanism heretofore employed; to make the mechanism responsive to a sensitive or delicate impulse; 20 to insure increased speed of operation; to facilitate the adjustment of the actuator; and to attain these objects in a simple and inexpensive structure.

To the above ends essentially my invention 25 consists in such parts and in such combinations of parts as fall within the scope of the appended claims.

In the accompanying drawings which form 30 a part of this specification

Figure 1 is a perspective view of my feeler mechanism showing a portion of its support broken away,

Figures 2 and 3, a top plan view and a front elevation respectively of my mechanism, the 35 frame cover being omitted in Figure 2,

Figures 4 and 5, fragmentary sections of the same on line 4—4 and 5—5 respectively of Figure 2,

Figures 6, 7 and 8, sections of my mechanism and of a shuttle, and of a bobbin diagrammatically displayed, taken on line 6—6 of Figure 3 showing three different positions of the feeler, and

Figures 9 and 10, sections of my mechanism taken on line 9—9 of Figure 9 showing the latch in two positions.

Like characters of reference indicate like parts throughout the views.

In the drawings 15 represents one end of the breast beam or frame of an ordinary loom 60 of the filling replenishing type. 16 is one of two end brackets in which is journaled the rock shaft 17 connected with the shuttle replenishing mechanism not shown. The rock arm 18 of the shaft is pivoted at 19 to 65 the forward end of an actuator plate 21, whose forward movement actuates, through the rock arm, the shuttle replenishing mechanism. The plate 21 is slidable edgewise upon the breast beam, adjacent which vibrates 70 the usual cam follower or weft hammer 22 actuated by the weft cam of the loom cam shaft in the customary manner. The upper end of the follower has integral therewith a lateral extension 24 disposed transversely of 75 and above the rear end of the member 21. The extension is provided along its forward lateral edge with a bevel 25 constituting a knife edge. A horizontal bearing extension 27 integral with an intermediate portion of 80 the plate 21 has upon its free end a depending cam block 28 provided with an upwardly and rearwardly inclined operating face 29 terminating in the plane of the top of the extension 27. Vertical guide lugs 31 and 85 32 spaced from each other upon the top of the block 28 form a guideway 33. A pivot pin 34 fixed in the lug 32 and plate 21 passes loosely through a transverse hole 35 in one end of the shank 36 of a gravity 90 catch represented generally by 37. An upright head 38 upon the free forward end of the arm 37 is provided in its rear face with a beveled recess 39 adapted under certain circumstances to receive knife edge 25 of the following extension 24.

A transmission rod 41 is provided near one end with a guide loop 42, and near its other end is a vertically bent portion 43 forming a right angular shoulder 44 slideable upon the face 29 of the fixed cam 28. The rod is again rectangularly bent, as at 45, and terminates in a resultant offset horizontal end portion 46 which extends through the guideway 33 and normally rests upon the extension 27. Upon the rod portion 46 rests the shank of the catch 37 which is elevated by the upward travel of the shoulder 44 upon the cam block 28 whenever the rod 41 is longitudinally impelled.

Upon the end of the breast beam 15 is the usual extension or skipper stand 49 to which

is attached by a bolt 50 a bracket 52 upon which is attached by a bolt 54 a rectangular block or frame 56, provided centrally with a transversely disposed cut away portion 57 in its top forming parallel flat shoulders 60 and 61 upon the front and back margins. A cover or retaining plate 62 is fixed by a screw 63 to the block. Near one end of the shoulder portion 60 of the block, as shown in Figure 2, is a transverse bore or hole 65, near its center, a similar hole 66; and near its other end, a transverse slot 67. In the shoulder 61 opposite the hole 66 and slot 67 respectively are a hole 68 and a slot 69. Communicating with the slot 69, as shown in Figure 9, is a hole 71 disposed at right angles thereto. Integral with the frame at opposite sides of the hole 71 are guide lugs 73 between which slides the loop 42 of the rod 41, and which cooperate with the loop to maintain the portion 43 of the rod in vertical position.

A feeler member, indicated in a general way by 75, is bent up from a length of wire, and includes a rod or shank 76, slidably mounted in the holes 68 and 66, a head 77 upon its rear end, a vertical loop 78 upon its forward end, merging in a horizontal loop 79 adjacent thereto, and a terminal stop finger 80 slidable in the hole 65 parallel with the shank 76, and adapted to abut against the shoulder 61. The member 75 is continually rearwardly pressed by virtue of a helical spring 81 attached at one end to the loop 78, and at its other end to a vertical pin 82 in the rear portion of the frame member 62.

An actuator member 83, also bent up from a length of wire, comprises an arm section 84 passing loosely through the slots 67 and 69 provided with a laterally inclined rear portion 85 terminating in a vertical finger 86; a horizontal lateral loop 87 upon the front end of the arm continuous with an arm section 88 disposed at substantially right angles to the first arm section; and a rearwardly directed vertical terminal loop 89 loosely engaging the loop 79 constituting a universal joint. The arm section 84 is normally in contact with the end of the rod 41. The slots 67 and 69 are of sufficient amplitude to permit the member 83 to swing laterally a limited distance.

In the drawings 91 is a shuttle carried in the usual manner by the loom lay, not herein shown, provided with a lateral slot 93 through which the feeler head 77 has access, as the lay reciprocates, to the filling 95 on the cop or bobbin spindle 96. In Figures 6 and 7 the shuttle is shown with a fully loaded spindle in a rearward and forward position respectively of the lay. In Figure 8 the position of the operative parts is shown at the instant of practical exhaustion of the filling.

In operation the feeler head 77 contacts

with the filling 95 at each stroke of the lay, the feeler yielding under the light tension of the spring 81 which immediately returns the head to original position. This operation is repeated until the finger 86 of the shorter actuator 83 receives the impact of the shuttle, as shown in Figure 8, whereupon the actuator is pushed to the right by the shuttle in the arc of a circle to a position shown in broken lines in Figures 2 and 8. This movement impels the rod 41 to the right from the position shown in Figure 9 to that shown in Figure 10, whereby the catch 37 is elevated to bring the recess 39 of its head 38 into the path of the edge 25 of the cam-follower extension 24, which in its forward reciprocation registers in the recess and forwardly impels the carrier plate 21, and thus operates the refilling mechanism.

The rearward reciprocation of the follower extension 24 releases the catch 37 which falls by gravity upon and depresses the end 46 of the rod 41 which thereby returns the member 83 to original position.

The contact finger 86 is adjustable towards and from the shuttle by means of compressing or expanding the loop 87.

It will be noted that the lateral movement of the actuating member is free and unimpeded by any spring attached thereto, or by any other impediment. That pivoted action is facilitated by the interlocking loops 79 and 89.

I claim:—

1. In a feeler mechanism for looms, a feeler block, a feeler member slidably transversely of the block at right angles to the path of a shuttle comprising a shank, a smooth triangular head upon the rear end of the shank, a horizontal loop upon the front end of the shank, and a stop finger integral with the loop parallel with the shank, a laterally movable actuator arm impellable by contact with a shuttle upon a detecting beat of the feeler head comprising a rear section including a rearwardly directed laterally inclined rear portion, a vertical finger upon the end of the rear portion, a second arm section disposed at substantially right angles to the first section, and a loop upon the end of the second section loosely engaging the horizontal loop, and a transmission rod upon the support in the path of the first section of the actuator arm.

2. In a feeler mechanism for looms, a feeler support comprising a rectangular block, vertical flat shoulders parallel with each other upon the front and back of the block provided with aligned transversely disposed holes and with aligned transversely disposed slots spaced from the holes, and a cover upon the shoulders, a pin upon the rear portion of the cover, a feeler member comprising a shank slidable in the block in the holes, a head upon the rear end of the shank, a vertical loop upon the rear end of the shank in trans-

- verse alignment with the pin, a horizontal lateral loop continuous with the first loop, and a rearwardly directed stop finger engageable with the rear shoulder of the block, a 5 swinging actuator arm comprising a rear section slidable in the slots and including a laterally inclined rear portion, a vertically disposed contact finger upon the rear portion of the arm section, a horizontal adjusting loop 10 upon the front end of the arm section, a second arm section disposed in front of the block continuous with the adjusting loop, and a vertical loop upon the second arm section loosely engaging the horizontal lateral loop, 15 a spring connecting the first mentioned vertical loop and the pin, and a transmission rod slidably mounted in the block in the path of the rear section of the actuator arm.
3. In a feeler mechanism for weft replenishing looms, a feeler supporting block, a 20 feeler member slidably mounted in the block,
- an actuator arm slidably mounted and laterally movable in the block pivotally attached to the feeler member, a slidably reciprocating actuator plate, a vibratory cam follower 25 movable longitudinally of the plate, a gravity latch pivoted to the side of the plate and movable into the path of the cam follower, a cam block fast to the side of the plate below the latch provided with an upwardly inclined cam face, a transmission rod slidably supported at one end in the block in the path of the actuator arm and longitudinally movable thereby and supported at its other end by the cam block in contact with the bottom 30 of the latch, and a vertical shoulder upon the rod movable upon the cam face to elevate the catch when the rod is impelled by the actuator arm.

In testimony whereof I have affixed my signature. 40

CLIFFORD G. MOON.
